United States Patent Office

Des. 175,490
Patented Sept. 6, 1955

175,490

SOUND TRANSLATING MACHINE

Leo J. Aucoin, Bantam, Conn., assignor to The Gray
Manufacturing Company, a corporation of Connecticut

Application December 15, 1954, Serial No. 33,568

Term of patent 14 years

(Cl. D26—14)

Fig. 1.

Fig. 3.

Des. 175,490

PAGE 2

Fig. 2.

Fig. 4.

Fig. 1 is a perspective view from a front corner, showing the front, top and one side of a sound translating machine showing my new design;

Fig. 2 is a plan view of the machine;

Fig. 3 is a side elevation thereof; and

Fig. 4 is a rear elevation on a slightly enlarged scale.

I claim:

The ornamental design for a sound translating machine, as shown.
